UNITED STATES PATENT OFFICE.

EDWARD L. BEHRING, OF WYKOFF, MINNESOTA.

DESIGN FOR A DISPLAY-STAND.

49,471.

Specification for Design.

Patented Aug. 1, 1916.

Application filed May 23, 1916. Serial No. 99,470. Term of patent 7 years.

To all whom it may concern:

Be it known that I, EDWARD L. BEHRING, a citizen of the United States, and a resident of Wykoff, in the county of Fillmore and State of Minnesota, have invented a new, original, and ornamental Design for a Display-Stand, of which the following is a specification, reference being had to the accompanying drawing, forming part thereof.

The figure is a perspective view of a display stand embodying my new design.

I claim:

The ornamental design for a display stand, as shown.

EDWARD L. BEHRING.

Copies of this patent may be obtained for five cents each, by addressing the "Commissioner of Patents, Washington, D. C."
